BEER COOLING KEG

Leland H. Floyd, Woodbridge, N. J., assignor of
one-half to Charles M. Hunsberger, Spring
Lake Heights, N. J.

Application February 7, 1939, Serial No. 255,125

1 Claim. (Cl. 257—14)

This invention appertains to new and useful improvements in cooling apparatus and more particularly to a beer cooling keg.

The principal object of the present invention is to provide cooling means for beer keg wherein the cooling means is constructed and arranged in such a manner as to obviate the necessity of bringing the beer into direct contact with the said means.

Another important object of the invention is to provide beer cooling means in the form of a specially constructed keg wherein a cooling medium is circulated in a manner which will afford a uniform cooling action to the entire periphery of the beer column.

These and various other objects and advantages of the invention will become apparent to the reader of the following specification.

In the drawing:

Figure 1 represents a top plan view.

Figure 2 is a side elevational view of the keg with portions in section.

Figure 3 is a fragmentary detailed sectional view on line 3—3 of Figure 1.

Referring to the drawing wherein like numerals designate like parts, it can be seen that the keg in construction consists of the outer shell 5 having the circumferentially extending ribs 6. Numerals 7 and 8 represent the upper and lower walls of the keg which are constructed in the usual manner and have their end portions clinched over the upper and lower edges of the shell 5 as at 9 and also over the upper and lower edges of the spaced walls 10 and 11. The upper and lower edge portions of the walls 10 and 11 are brought together and offset outwardly as shown clearly in Figure 2 to a point to meet the upper and lower edges of the shell 5 where the upper and lower walls 7 and 8 are clinched over the same and further secured in any desired manner. Numeral 12 represents the usual bung and numeral 13 represents the usual eduction tube fitting.

In further carrying out the present invention, a tube 14 extends inwardly from the top wall 7 into the space 15 between the walls 10 and 11. This tube 14 is in the form of a coil extending downwardly in the space 5 and having its lower extremity 16 open at the bottom of the space 15. A pair of couplings 17 and 18 are provided at the top wall 7 adjacent the edge thereof and preferably overlying the space 15 and each of these fittings 17 and 18 consists of a socket 19 having bayonet slots 20 in the upper portion thereof. These sockets 19 can be welded or otherwise secured as at 21 to the top 7 and each has a skirt portion a which depends through the top

7 and also through the offset portion of the inner wall 10.

Tubes 22 of hard rubber or other similar material are disposable into the sockets 19 and each carries a transversely disposed pin 23 the end 5 portions of which fit into the bayonet slot 20. The lower portions of the tubes 22 are provided with reduced depending tubular portions 24 over which can be slipped, in the case of the inlet fitting 17, the upper end of the tube 14, with the upper edge portion of the tube 14 flared outwardly against the internal shoulder of the corresponding socket 19. Gaskets 25 are provided in the sockets to serve as packing means.

The upper ends of the tubes 22 are tapered as 15 at 26 and over these are slipped the rubber inlet and strain-off tubes 27 and 28 respectively.

It can now be seen that refrigerated liquid such as water is supplied to the coil 14 through the tube 27 and passes downwardly through the convolutions of the coil 14 and discharges from the open lower end 16 of the tube 14 into the bottom of the space 15. As the walls 10 and 11 bear snugly against the convolutions of the coil 14, the coil will serve as a baffle and require the refrigerated liquid to pass upwardly following the coil 14. In other words, the upward passage of the refrigerated liquid must follow the convolutions of the coil and in this way complete contact of the outer side of the wall 10 is accomplished with the refrigerated liquid before it reaches the outlet fitting 18 where it is drawn off. This serves of course to cool the entire area of the wall 10 affording a uniform cooling action against the periphery of the beer column.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

A beer keg comprising a container having spaced walls, a pre-cooled liquid inlet at one end of the keg, a coil in the space between the walls communicating at one end with the inlet and having its opposite end open, said container having an outlet at the inlet end of the container in communication with the space between the walls, said walls snugly fitting against the said coil to define the coil as a baffle to form a spiral passage-way in the space between the walls for the return of the pre-cooled liquid from the open end of the coil to the outlet of the container.
